US00D868802S

(12) **United States Design Patent** (10) Patent No.: **US D868,802 S**
Tzeng et al. (45) Date of Patent: ** Dec. 3, 2019

(54) **DISPLAY SCREEN OR PORTION THEREOF WITH GRAPHICAL USER INTERFACE**

(71) Applicant: **GE Inspection Technologies, LP**,
Lewistown, PA (US)

(72) Inventors: **Bright Tzeng**, San Ramon, CA (US);
Min Chang, San Ramon, CA (US);
James Lee, San Ramon, CA (US)

(73) Assignee: **GE INSPECTION TECHNOLOGIES, LP**, Lewistown,
PA (US)

(**) Term: **15 Years**

(21) Appl. No.: **29/649,870**

(22) Filed: **Jun. 1, 2018**

(51) LOC (12) Cl. **14-03**

(52) U.S. Cl.
USPC **D14/485**

(57) **CLAIM**

The ornamental design for a display screen or portion thereof with graphical user interface, as shown and described.

DESCRIPTION

FIG. 1 is a front view of a display screen or portion thereof with graphical user interface showing a first image of our new design; and,

FIG. 2 is a front view of a second embodiment thereof. The broken lines in the Figures show portions of a display screen or portion thereof with graphical user interface and portions of the display screen or portion thereof which form no part of the claimed design.

1 Claim, 2 Drawing Sheets
